UNITED STATES PATENT OFFICE.

ADELINE M. WALKER, OF ELIZABETH, NEW JERSEY, AND FRANCES C. JACKSON, OF NEW YORK, N. Y.

DESIGN FOR A GARMENT-HANGER.

SPECIFICATION forming part of Design No. 28,448, dated April 5, 1898.

Application filed October 1, 1897. Serial No. 653,754. Term of patent 3½ years.

To all whom it may concern:

Be it known that we, ADELINE M. WALKER, a resident of the city of Elizabeth, county of Union, and State of New Jersey, and FRANCES C. JACKSON, a resident of the city, county, and State of New York, citizens of the United States, have invented and produced a new and original Design for a Garment-Hanger, of which the following is a specification.

10 We have illustrated our garment-hanger in the accompanying drawing.

The figure is a plan view of our device with the legs of the pins unclasped.

15 The garment-hanger is a substantially flat device formed by a single piece of wire and clasps attached to its sides as follows: A piece of suitable material with sharpened ends is bent at the middle to form the circular loop A, and at the bottom of the loop, at 20 a' and a' , the free ends are bent at almost right angles to the loop and in the same place therewith and parallel to each other and forming the backs b' and b' of the pins B and B. At b^2 and b^2 the end wires are bent upward, but in opposite directions, as shown in

the drawing, forming the prongs or hooks b^3 and b^3 with the points b^4 and b^4 and substantially parallel to the shanks b' and b' .
c and c are clasps attached to the sides of the loop A.

30 As shown in the drawing, the leading or material feature of our design consists of a circular body or loop at the top of the hanger and two hooks or pins extending from said loop and placed side by side in relation to 35 each other, the hooks or pins pointing in opposite directions.

Having fully described our new and original design, what we claim, and desire to secure by Letters Patent, is—

40 The design for a garment-hanger herein substantially as shown and described.

Signed at New York, in the county of New York and State of New York, this 25th day of September, A. D. 1897.

ADELINE M. WALKER.
FRANCES C. JACKSON.
